UNITED STATES PATENT OFFICE.

PHILLIP BAKER, OF MATTAPAN, MASSACHUSETTS, ASSIGNOR TO PARAMOUNT BEDDING MACHINE CO., OF BOSTON, A CORPORATION.

MATTRESS-FILLING MACHINE.

Application filed February 17, 1926. Serial No. 88,794.

The present invention relates to an improvement in mattress filling machines.

The object of the invention is to reorganize and improve mattress filling machines, and to this end the invention consists in the machine hereinafter described and particularly defined in the claims.

The accompanying drawing illustrating the preferred form of the invention is an elevation.

The filling material, such as kapok, is introduced in the hopper 10, from which it passes through the pipe 11 to the blower 12. This blower discharges through the riser pipe 13 and pipe 14 into the tank 15. The pipe 14 is a horizontal conveyor pipe, provided in its lower side with a wire screen 16, which allows any dust or stems or dirt to pass through into the dirt box 17. A door 18 on the front of this dirt box is provided to enable the dirt to be removed. At the advance end of the dirt box is an open pocket 19, which may catch nails or small pieces of stone or things of this sort which might be found in the filling material. A similar pocket 20 is provided at the other end of the dirt box. The tank 15 comprises a large sheet metal receptacle having a series of grate bars 21 projecting radially toward a beater 22, the arms of which pass between the bars of the gratings 21 and serve to stir up, loosen and prepare the material for use as a mattress filler. A wire screen 23 is provided which extends around the lower portion of the tank below the beater through which dirt and refuse such as stones, sticks and the like may pass into the dirt chamber 24. Doors 25 are provided for permitting access to the dirt chamber 24 to remove the dirt therefrom.

The tank 15 is connected by a throat 26 with a second tank 27. In the throat is a damper 28 by which the tank 15 may be closed so as to retain any material being treated in the tank 15. The material passing from the tank 15 through the throat 26 into the lower tank 27 is again subjected to the action of a beater 29, which cooperates with grate bars 30, having fingers arranged radially of the beater arms of the beater 29, so as to further treat the fibre being operated upon by the machine. The lower tank is provided with wire screens 31 which permit dirt to collect in the dirt chamber 32, a door

33 being provided for access to this dirt chamber to clean it.

The material, after being beaten in the lower tank, will be withdrawn through the pipe 34 and carried through that pipe to the blower 35, a dirt box 36 being provided on the lower side of this pipe like the dirt box 17 above described. From the fan 35 the material is discharged through the riser pipe 36' into the horizontal pipe 37, similarly provided with a dirt box 38. This pipe is provided with an air intake netting 39 in its top, through which air may enter the pipe 37 when demanded by the operation of the machine.

From the pipe 37 the material is discharged into the pipe 40, through which it descends to the mouthpiece or nozzle 41, through which the mattress filling material is discharged into the mattress. A flap damper 42 is provided at the junction of the nozzle 41 with the pipe 40, by means of which the nozzle may be closed when desired. The lower part of the pipe 40 leads back to the pipe 34. A damper 43 is provided in the pipe 34, and when it is opened, material from the lower tank 27 is carried from that tank into the fan 35.

The tank 15 is provided at its top with a wire netting closed cover 44 to permit the entrance and emission of air from the tank 15. This tank is also provided with a door 45, by means of which access may be had to the interior of the tank for the purpose of cleaning it and removing any collected material from the beater. A similar door 46 is provided in the top of the lower tank 27.

The operation of the machine is as follows: The mattress filling material, which is kapok, feathers, or what not, is introduced into the receiving hopper 10, carried to the blower 12, and thence discharged into the top beater tank 15, where it is beaten up by the action of the beater. At this time the damper 28 in the throat 26 will be closed, and as much material will be fed into the upper tank as is consistent with its good operation. After this is fairly well beaten and cleaned in the upper tank, it will be dropped into the lower tank by opening the damper 28, after which the damper will be again closed, and the upper tank will be in a condition to receive another supply of

mattress filling material at the same time that the material in the lower tank is being subjected to a secondary beating operation therein. After the material has been properly beaten in the lower tank, and when it is desired to fill the mattress, the latter will be presented to the nozzle 41, the damper 43 leading to the lower tank will be opened and the material therein will be drawn out by the fan 35, admission of air to the lower tank being provided by the screen cover opening 47. The material thus discharged into the blower fan 35 will be carried by it to the nozzle 41 and discharged into the mattress. Upon completing the filling of a mattress the damper 42 will be swung from the position shown, to a position closing the nozzle, and such material as is in the mattress filling system shown at the left of the drawing will be permitted to circulate through the fan until another mattress is ready to receive the material therein.

The machine is adapted to subject the filling material to three cleaning operations by carrying it over the three dirt boxes in the three horizontal legs or lengths of the conveyor piping. The material first put into the machine will be carried immediately to the upper tank which will at that time be separated from the lower tank by the closure in the throat, and will there be subjected to a preliminary beating operation. Then this material will be dumped into the lower tank and subjected to a further beating operation at the same time that a second charge is being received in the upper tank and being beaten therein. Then while the upper tank is still operating on the material contained therein, the material from the lower tank will be drawn off and inserted in a mattress.

Having thus described the invention, what is claimed is:

1. A machine for treating mattress filling having, in combination, two superposed tanks, a beater in each tank, means for delivering material to the upper tank, a connection between the tanks to permit material to fall by gravity from the upper to the

lower tank for a secondary beating operation in the latter while a fresh charge is being simultaneously beaten in the former, a closure in the connection, a blower, a pipe leading from the second tank to the blower, and a discharge pipe connected with the blower.

2. A machine for treating mattress filling having, in combination, a tank, a beater in the tank, a pipe leading from the tank, a blower, a discharge nozzle connected with the blower, and connections independent of the beater for permitting a continuous circulation therein and through the blower of material in excess of that required at any given time while additional material is being operated upon in the beater.

3. A machine for treating mattress filling having, in combination, two superposed tanks, a beater in each tank, means for delivering material to the upper tank, a connection between the tanks to permit material to fall by gravity from the upper to the lower tank for a secondary beating operation in the latter while a fresh charge is being simultaneously beaten in the former, a closure in the connection, a blower, and circulatory piping and having provision for circulation therein, independent of the operation of the beaters, of material in excess of that required at any given time.

4. A machine for treating mattress filling having, in combination, a tank, a beater in the tank, means for delivering filling material to the tank, discharging means for the tank comprising a blower, a blower feed pipe leading from the tank to the blower intake, and a blower discharge pipe leading from the blower discharge to and connecting with the blower feed pipe, said blower discharge pipe being provided with a filling discharge mouth having a closure, operating when open, to discharge filling from the tank at the mouth and, when closed, to circulate the filling to keep it from clogging the pipe.

In testimony whereof I have signed my name to this specification.

PHILLIP BAKER.
